US00D881301S

(12) **United States Design Patent** (10) **Patent No.:** **US D881,301 S**
Jin (45) **Date of Patent:** **** Apr. 14, 2020**

(54) **RESISTANCE BANDS WITH CUFFS**

(71) Applicant: **Qiuwang Jin**, Shenzhen (CN)
(72) Inventor: **Qiuwang Jin**, Shenzhen (CN)
(**) Term: **15 Years**
(21) Appl. No.: **29/715,183**
(22) Filed: **Nov. 28, 2019**
(51) LOC (12) Cl. **21-02**
(52) U.S. Cl. **USPC D21/692**

(58) **Field of Classification Search**

USPC D21/797, 698, 662, 683; 482/23, 48, 482/139, 44, 105; 2/161.1, 162, 170, 2/917, 16, 20; D8/330, 303; D20/22; D29/113, 120.1, 791, 797, 190, 117.1; 473/205; D24/190

Primary Examiner — Ryan Harvey

(57) **CLAIM**

The ornamental design for a resistance bands with cuffs, as shown and described.

DESCRIPTION

FIG. 1 is a front perspective view of a resistance bands with cuffs showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The claimed design is shown with a symbolic break in its length. The appearance of any portion of the article between the break lines forms no part of the claimed design.

1 Claim, 8 Drawing Sheets---
